UNITED STATES PATENT OFFICE

LEONARD FRIEDBERG, OF NEW YORK, N. Y., ASSIGNOR TO PARIS COSMETICS, INC., OF NEW YORK, N. Y., A CORPORATION OF NEW YORK

DESIGN FOR A VANITY CASE

Application filed June 4, 1929. Serial No. 31,541. Term of patent 7 years.

To all whom it may concern:

Be it known that I, LEONARD FRIEDBERG, a citizen of Poland, and a resident of the city of New York, borough of Manhattan, in the county of New York and State of New York, have invented the new, original, and ornamental Design for a Vanity Case, of which the following is a specification.

Reference is to be had to the accompanying drawings, forming a part hereof in which

I claim:

The ornamental design for a vanity case as shown.

Signed at city of New York in the county of New York and State of New York this 24th day of May, A. D. 1929.

LEONARD FRIEDBERG.
